UNITED STATES PATENT OFFICE.

FRANK. MARTIN AND GEORGE MARTIN, OF MILWAUKEE, WISCONSIN.

FULLING-MILL.

SPECIFICATION forming part of Letters Patent No. 443,722, dated December 30, 1890.

Application filed January 27, 1890. Serial No. 338,229. (No model.)

To all whom it may concern:

Be it known that we, FRANK. MARTIN and GEORGE MARTIN, of Milwaukee, in the county of Milwaukee, and in the State of Wisconsin, have invented certain new and useful Improvements in Fulling-Mills; and we do hereby declare that the following is a full, clear, and exact description thereof.

Our invention relates to fulling-mills; and it consists in certain peculiarities of construction and combination of parts, to be herein-after described with reference to the accompanying drawings and subsequently claimed.

In the drawings, Figure 1 represents an elevation of our mill, partly in section; Fig. 2, a plan view, partly in horizontal section; and Fig. 3, a detail sectional view of one form of corrugated surface that constitutes part of our mill.

Referring by letter to the drawings, A represents two standards inclined toward each other and connected at the top by a cross-beam B to form the main frame of our mill. Pivotaly connected to the cross-beam B are vertically-disposed arms C, shackled to pitmen D, that connect with the cranks b of a shaft E, the latter having its bearings on posts F, connected to one of the standards A by means of a brace G, as shown by Fig. 1.

The arms C extend down into a receptacle H and carry beaters I, the latter being tapered and corrugated at the ends. The receptacle H is provided upon its interior with a curved plate J, having a central opening c, and be-

tween this plate and the bottom K of said receptacle we arrange a steam-coil L, for the purposes to be hereinafter described. The bottom K of the receptacle is provided with a trap d to receive the dirt that is dislodged

from the material under treatment and falls through the opening c in the plate J during the operation of the mill. The plate J is not equal in length to the receptacle H, and extending up from each end of said plate to the

top of said receptacle is a corrugated surface in opposition to the ends of the beaters I, the latter being reciprocated in opposite directions by the crank-shaft and pitman mechanism above described. As shown in Figs. 1 and 2, the corrugated surface consists of a series of ribbed rollers M, journaled in the sides of the receptacle H, and we prefer to

provide each roller with a ratchet-wheel e for engagement with a spring-actuated dog f, whereby said roller is held against rotation 55 except in the desired direction, the latter being the same for all the rollers in the series. The corrugated surface may consist of a series of slats connected to endless chains or belts to form an apron R, that runs on rollers 60 S, as shown in Fig. 3.

Our fulling-mill is particularly designed for the treatment of fur-skins, the latter being packed in a dry state between the beaters and the corrugated surfaces, steam let into the 65 coil, and the crank-shaft rotated to reciprocate said beaters. Enough heat radiates from the steam-coil to melt the grease on the skins, and the latter, being pounded by the beaters against the corrugated surfaces, are softened 70 by this mechanical treatment and by the absorption of said grease. The corrugated surfaces are rotated by the frictional contact therewith of the fur-skins and the impact of the beaters, and said skins being constantly 75 changed as to position by the rotation of the said corrugated surfaces the bunching that would otherwise result is avoided.

We are aware that the beaters and their actuating mechanism are not new of themselves, and we do not wish to be understood as claiming the same, except in combination with such other features as may be novel in the art to which our invention relates.

We are also aware that corrugated rollers 85 are not broadly new in fulling-mills.

Having thus described our invention, what we claim as new, and desire to secure by Letters Patent, is—

1. In a fulling-mill, the combination, with 90 reciprocating beaters, of corrugated rollers arranged in series opposite said beaters, ratchet-wheels arranged on the rollers, and spring-actuated dogs for engagement with the ratchet-wheels, substantially as set forth.

2. In a fulling-mill, the combination of a receptacle, beaters reciprocating therein, a plate of less length than the receptacle arranged in the latter beneath the beaters, a corrugated surface extended up from each end of the 100 plate to the top of said receptacle, and a steam-coil arranged beneath said plate, substantially as set forth.

3. In a fulling-mill, the combination of a

receptacle, beaters reciprocal therein, a curved plate of less length than the receptacle arranged in the latter beneath the beaters and provided with a central opening, a trap 5 in the bottom of said receptacle in register with the plate-opening, and a corrugated surface extended up from each end of the plate to the top of said receptacle, substantially as set forth.

In testimony that we claim the foregoing we to have hereunto set our hands, at Milwaukee, in the county of Milwaukee and State of Wisconsin, in the presence of two witnesses.

FRANK. MARTIN.
GEO. MARTIN.
